UNITED STATES PATENT OFFICE.

GEORGE GOLDSMITH GRUNEWALD, OF PERRYSVILLE, AND MARY SWEET, OF MIFFLIN,
OHIO.

PERPETUAL CALENDAR.

1,426,982.

Specification of Letters Patent. Patented Aug. 22, 1922.

Application filed January 21, 1922. Serial No. 530,830.

To all whom it may concern:

Be it known that GEORGE GOLDSMITH GRUNEWALD and MARY SWEET, citizens of the United States of America, residing at 5 Perrysville and at the village of Mifflin, respectively, in the county of Ashland and State of Ohio, have invented certain new and useful Improvements in a Perpetual Calendar, of which the following is a specification.

This invention relates to an improvement in calendars of the perpetual or continuous type, wherein through the manual adjustment of one or more parts arranged for such 15 adjustment, the calendar may be set for any month of any year desired.

The improved calendar includes two movable elements or disks, one adjustable to set the calendar for the desired month, and 20 the other adjustable to set the calendar for the desired year; the calendar also including certain fixed data, designed for cooperation with the data of the year disk and with the data of the month disk, in order to complete 25 the reading relation of the calendar data as a whole when set for a particular month of a particular year.

The detailed arrangement is more particularly shown in the accompanying drawings, in which:—

Fig. 1 is a face view of the completed calendar.

Fig. 2 is a rear view of the same.

Fig. 3 is a section on line 3—3 of Fig. 1.

35 Fig. 4 is a plan view of the month disk.

Fig. 5 is a plan of the year disk.

The improved calendar is preferably mounted in a rectangular frame 1, having a glass-protected face opening 2, through 40 which the data of the calendar is visible. The rear of the frame is covered by a back-plate 3, which together with the side bars of the frame is cut away at 4 to permit convenient access to the means for operating 45 the year and month disks.

A sheet 5 of appropriate material, as cardboard, is secured against movement within the frame, immediately below the glass covering the opening 2. This sheet, is provided 50 with fixed data and will be hereinafter termed the fixed-data sheet and is formed immediately below its transverse median line with an opening 6, through which the data

on the year disk and on the month disk is visible as a determining aid in properly adjusting such disks.

Below the opening 6, the fixed-data sheet is provided, by printing or otherwise, with fixed year data, indicated generally at 7. This fixed year data consists of radial 60 columns of circumferential rows of figures, arranged in the present instance to specifically represent the first two figures of a series of years, that is the century years indications. For example, the column at the 65 extreme right of Fig. 1 is headed by the century number 15, the succeeding columns toward the left being headed by the next succeeding century number. The second circumferential row beginning at the column 70 immediately to the left of the "15" column begins with the initial number of the final column, the remaining numbers of this row being consecutive, and so on throughout this particular data. Certain of these columns 75 are printed in contrasting colors, as in red, indicated by non-solid figures, and these columns are for centuries each ending with a leap year.

The data just described is for the so-called 80 new style of calendar reckoning, and below this data 7, and preferably distinctively divided therefrom by a division line 8, is a similar series of radial columns made up of 85 rows of figures, all printed in the contrasting color, as each century under this style of reckoning ended with a leap year. This particular yearly data, indicated generally at 9, is for calendar reckoning for the years preceding the commencement of the present 90 style, that is prior to October 15, 1582. The particular arrangement of the data of this yearly style is clearly apparent from the drawings, the consecutive arrangement of the years being followed as in the present 95 style of reckoning.

The fixed-data sheet 5, above the opening 6, is provided by printing or otherwise with the numbers 1 to 31, indicating the days of the month. This monthly data, shown at 10, 100 is arranged in seven vertical rows and five transverse rows, numbered consecutively and transversely from 1 to 31 in the spaces thus provided. Immediately above this monthly data 10, the fixed-data sheet is provided with 105 an elongated curved aperture 11, through

which the days of the week become visible in the adjustment of the disks, as hereinafter explained.

A yearly disk 12 is mounted on a central pivot 13, immediately below the fixed-data sheet. This yearly disk has a series of numbers, indicated generally at 14, arranged in concentric rows and radial columns. These numbers are designed to present the final 10 year-figures of the centuries for which the calendar is being adjusted, that is, with a particular number in this data aligned radially with the column of the data 7 containing a particular number, the said two 15 numbers represent a certain year in the calendar adjustment. For example, with the column of the data 14 on the year disk arranged in alinement with any column of the data 7 of the fixed-data sheet, the century indication is complete for any years indicated by two numbers of one column and two numbers of the other column. Thus 1922 would be indicated by alining the column of the data 14 containing "22" with the column of the data 7 containing "19."

The year disk is also formed with eight openings 15, arranged in a concentric series and adapted to be positioned in the opening 6 of the fixed-data sheet 5 at each yearly adjustment of the calendar. These openings 15 constitute openings through which certain data on the month disk is visible. The year disk is also formed with a narrow opening 16, concentric with but beyond the 30 yearly data thereon, this annular opening registering with the aperture 11 under all conditions. The opening 16 is preferably bridged by radial division bars 17 to maintain the integrity of the year disk, and 40 also to provide clear lines of division between the days of the week, it being clearly apparent from the drawings that in any proper adjustment of the year disk, the bars 17 align with the vertical divisions of the data 10.

The month disk is mounted on the pivot 13 immediately below the year disk. The month disk has an annular series of month indications, as at 18, these including the 50 names of the months, and also preferably a number corresponding to the number of days in that month. These month indications are so arranged on the month disk 19, that in the adjustment on its pivot, a selected month may be made visible through the 55 particular opening 15 of the year disk, which is then within the opening 6 of the fixed-data sheet, following the proper yearly adjustment of the year disk. The month disk has 60 also a series of week-day indications—that is the names of the days of the week—as indicated at 20. This data is arranged beyond the monthly data 18 and so spaced that in the adjustment of the month disk, such data will appear through the openings 11

and 16, and directly above the monthly data 10.

The year disk is preferably provided with an annular rim 21 formed with notches 22, accessible in the spaces 4 at the rear of the frame, and the month disk has a similar rim or base 23, formed with finger depressions 24, whereby either month or year disk may be rotated at will and accurately adjusted in accordance with the desired calendar indications. 75

It is believed that the operation of the parts in adjusting the calendar for a particular period, will be apparent from the above description taken in connection with the drawings. It will be apparent that following the adjustment of the year disk to set the parts for the particular year desired, as above described, an adjustment of the month disk may be had to show the particular 85 month. The weekdays and dates for that particular month in the desired year, are then correctly indicated on the calendar.

Attention is called to the fact that the leap year figures on year disk is indicated 90 in red and are divisible by four (4). When finding a leap year date for example 1924, the red figures "24" are used for January and February only, while the similar black figures to the left of the red column are for 95 the other months of the year. All other of the black figures on the disk are for years other than leap years.

The numbers below the disks are centuries or left hand figures of the dates. The figures 100 to be indicated in red are figures of centuries ending with a leap year and are divisible by 400.

The black figures being non-leap year centuries. 105

To set the calendar for any date the upper disk is turned so that the figures will be directly above the century figures below the disk. This completes the year sought. Then turn the lower disk till the month wanted appears in the opening of the upper disk; the day of the week will then appear above the date of the permanent month showing 31 days on the face of the calendar.

Attention is further called to the fact that 115 the calendar is mathematically accurate and reckons time from the year A. D. 1 to 3299. It will also be apparent that any date of the week of any date within its reckoning can be readily found of a past or future date. 120 In adjusting the calendar from month to month for continued use the lower disk is turned until the succeeding month appears in the opening by turning the outer disk forward one year adjusted for that year. 125

Having thus described the invention, what is claimed as new, is—

1. In a perpetual calendar, having a fixed data sheet with part year indications thereon, said sheet also bearing successive month 130

- dates and having openings formed therein in spaced apart relation to each other, a revolving disk having an annular rim provided thereon and having endorsed thereon 5 the remaining year indications, said disk also having spaced apart openings provided therein, a second disk fitted within the annular rim of the first disk and having notches formed on the rear portion therein 10 to revolve it adjacent to the year disk, said disk also having monthly indications endorsed thereon and indications of the days of the week arranged in association with the dates on the fixed data sheet as and for the 15 purpose described.
2. In a perpetual calendar, a fixed data sheet having part year indications endorsed thereon and separated to indicate the new style and old style calendar years, said fixed 20 data sheet also having successive month dates endorsed thereon and also having spaced apart openings provided therein, a disk having the remaining year data indicated thereon and having a concentric series 25 of openings formed therein, a month disk having monthly indications thereon and concentrically arranged indications of the days of the weeks endorsed thereon and means to separately rotate the month disk 30 and the year disk, to expose the data through the openings as and for the purpose described.
3. In a perpetual calendar having a fixed data sheet with part year indications there- 35 on arranged in radial columns, said part year indications indicating the old and new style calendar and a year disk having columns representing the remaining year indications, said year disk being adjustable to 40 arrange the year indications in radial columns with either set of the year indications of the fixed sheet.
4. A perpetual calendar having a monthly disk and a fixed data sheet with part year 45 indications thereon and arranged in radial columns, said part year indications indicating the old and new style calendar and a year disk having columns representing the remaining year indications, said year disk 50 being adjustable to arrange the part year indications in radial columns with either set of the part year indications of the fixed sheet and openings provided in the fixed data sheet and the part yearly data sheet to 55 expose to view the names of the days of the week on the monthly disk alined with pre-determined dates.
5. A perpetual calendar having a fixed data sheet bearing part year indications, the 60 dates of the month and having openings provided therein in spaced apart relation, a revolving disk mounted to revolve to expose certain data through the openings in the fixed data sheet, said revolving disk also 65 having openings provided therein, a sec- ond revolving disk mounted to revolve in association with and independently of the first revolving disk and having data provided thereon that will be exposed to view through the openings provided in the first 70 disk and fixed data sheet, both of said disks being journaled in a casing provided with openings in the rear portion thereof and having finger notches formed thereon to permit rotation of the disks relative to each other, for the purpose of exposing pre-determined data through said openings, to aline same with data on the fixed data sheet.
6. A perpetual calendar having a fixed data sheet bearing part year indications, the 80 dates of the month and having openings provided therein in spaced apart relation, a revolving disk mounted to revolve to expose certain data through the openings in the fixed data sheet, said revolving disk 85 also having openings provided therein, a second revoluble disk mounted to revolve in association with and independently of the first revolving disk and having data provided thereon that will be exposed to view 90 through the openings provided in the first disk, both of said disks being so arranged and associated together to indicate the day of the week of any particular date either prior to or subsequent to the instant date, 95 and both of said disks being journaled in a casing provided with openings in the rear portion thereof and having finger notches formed thereon to permit rotation of the disks relative to each other, for the purpose 100 of exposing pre-determined data through said openings, to aline same with data on the fixed data sheet.
7. In a perpetual calendar comprising a fixed data sheet having pre-determined data 105 endorsed thereon and openings formed therein, two disks mounted in association with said fixed data sheet and adapted to be rotated independently of each other, one of said disks also being provided with openings 110 and both of said disks being provided with pre-determined data, said pre-determined data being so arranged on the disks and fixed data sheet as to afford means of indicating the name of the particular day of the 115 week of a pre-determined date, either before or after the instant date, both of said disks being journaled in a casing provided with openings in the rear portion thereof and having finger notches formed thereon 120 to permit rotation of the disks relative to each other, for the purpose of exposing pre-determined data through said openings, to aline same with data on the fixed data sheet, as and for the purpose described. 125
8. In a perpetual calendar, comprising a fixed data sheet having a series of openings formed therein and two independently revolving disks, one of which is also provided with openings and having data endorsed 130

- on said fixed data sheet and revolving disks, whereby upon the actuation of the disks with relation to the data on the fixed disk, the data on all elements can be arranged 5 with relation to each other to indicate the name of the day of the week of a certain date, both of said disks being journaled in a casing provided with openings in the rear portion thereof and having finger notches 10 formed thereon to permit rotation of the disks relative to each other, for the purpose of exposing pre-determined data through said openings, to align same with data on the fixed data sheet, as and for the purpose described.
9. A perpetual calendar having a fixed data sheet bearing part-year indications, a year disk adjustable relative to such sheet and bearing the remainder of the year indications, the association of the year indica- 15
- 20

tions on said sheet and year disk determining the position of the year disk, and a month disk having month-data adapted for adjustment to disclose monthly data through an opening in the adjusted year disk. 25

10. A perpetual calendar having a fixed-data sheet with part-year indications thereon, said sheet also bearing the successive month-dates, a year disk having the remaining year indications and formed with openings, and a month disk having month designations visible through the openings of the year disk, and week-day indications to align with the month-dates of the fixed-data sheet. 30

In testimony whereof we affix our signatures.

GEORGE GOLDSMITH GRUNEWALD.
MARY SWEET.
